SPIRAL LOCK BINDING

Hullett Desbarats, Montreal, Quebec, Canada

Application May 28, 1934, Serial No. 727,928

6 Claims. (CL. 281—19)

This invention relates to binding and particularly to the binding of spiral bound sheets.

The bundle of sheets have a series of spaced perforations close to one edge, through which a spiral coil of wire is run.

The object of the invention is to provide a simple and inexpensive means of securing together two or more sets of spiral bound sheets.

A further object is to provide a simple and inexpensive means of attaching a cover to spiral bound sheets.

A further object is to provide means of attaching a cover to a series of connected sets of spiral bound sheets.

Other objects will be set forth hereinafter.

The invention in its simplest form consists in interlapping the spiral binding of two sets of sheets and then running a rod through the space included in both coils.

Other applications will be described which include additional elements and varied arrangements.

Reference will be made to the accompanying drawing in which:—

Figure 1 shows the attachment of two spiral coils in section.

Figure 2 shows a spiral coil inserted in a strip of leather.

Figure 3 is a plan view of Fig. 2.

Figure 4 shows a spiral coil in the back of a cover having backing strip.

Figure 5 shows a set of spiral bound sheets attached to a cover.

Figure 6 shows a plurality of attached spiral bound sheets secured to a cover.

Figure 7 shows a locking bar.

In Figure 1 the sheets 1 having perforations 10 are bound by the spiral coil 11 and the sheets 2 having perforations 20 are bound by the spiral coil 21. The coils are interlapped to form a space 3 through which a bar 4 is passed.

The bar 4 has a head 40 and a removable knob or nut 41.

In Figure 2 the part 5 is a flexible strip of leather or the like with two rows of perforations 50—50 staggered to receive a spiral coil 51 as shown in Fig. 3.

In Figure 4 the strip 5 joins the cover boards 52—52 which are also joined by the backing strip 53. In Figure 5 the spiral coil 51 in the perforations 50 is secured to the coil 11 which binds the sheets 1 by the bar 4.

In Figure 6 the strip 5 has two spiral coils spaced apart secured to it in perforations.

A series of sets of sheets 6 connected by spiral

binding as shown in Figure 1 has its end coils 61 attached by bars 4 to the coils 51—51. Cover boards 52—52 and a backing strip 53 are also provided.

In Figure 7 the bar 4 has a fixed knob 40 and a removable knob 41.

By means of this invention spiral bound books or magazines can be readily and rapidly joined together without affecting the flat opening of this type of binding.

By inserting a spiral coil in perforations of a flexible strip and attaching the edges of the strip to cover boards, spiral bound books or magazines can be readily secured to the covers. When a number of attached spiral bound books are to be provided with a cover, two spiral coils can be inserted in the leather back of the cover, and the outside coils of the books are then attached to the coils in the back strip.

To protect the strip bearing the coil of coils, an outer strip attached to the side boards of the cover may be provided.

This cover will furnish a permanent binding in which insertions or removals may be made when desired.

The invention is particularly adapted to the binding of periodicals, records, and refills.

By having a locking removable knob to the locking rod, an insert may be locked to a cover.

The invention can be readily adapted to a great variety of uses.

By means of the invention thick catalogues or directories can be bound in sections by spiral coils and made available to be opened flat.

What I claim is:—

1. An interlocking binding, comprising two spiral coil bound bundles of sheets having their coils interlapped and a rod running between the interlapped parts of the coils.

2. An interlocking binding, comprising a cover having a back and sides, a spiral coil inserted in two rows of perforations in the back, a bundle of sheets spiral bound by means of a second coil, having the two coils interlapped and a rod running between the interlapped parts of the coils.

3. An interlocking binding, comprising a cover having a back and sides, a spiral coil inserted in rows of perforations at each side of the back, a plurality of spiral bound bundles of sheets interlocked by bars in series, and each end coil interlocked by a bar with one coil of the back.

4. In an interlocking binding, a cover comprising, sides, a flexible inner back and an outer back, the inner back having a spiral coil in two

rows of perforations, adapted to interlap with the coil of a spiral bound bundle of sheets.

5. In an interlocking binding, two spiral coils interlapped, a rod running between the interlapped parts having end knobs, one of which is removable.

6. In an interlocking binding, a cover, a perforated flexible strip secured in the cover, a spiral coil inserted in the perforations, a spiral coil bound bundle of sheets, the coils interlapped and a rod through the interlapped parts of the coils.

HULLETT DESBARATS.
